(57) **CLAIM**

The ornamental design for the unit dose vial, substantially as shown and described.

DESCRIPTION

FIG. 1 is an isometric view showing the unit dose vial of my new design;

FIG. 2 is a top plan view of the unit dose vial, the bottom plan view being the same;

FIG. 3 is a side elevational view of the unit dose vial, the opposite side elevational view being the same;

FIG. 4 is an end elevational view of the unit dose vial; and, FIG. 5 is an end elevational view of the unit dose vial of the end opposite the end shown in FIG. 4.
